Design for Shawls

Fig. 2.

Inventor
Walter Sandenberger
and Alexander Massa
Attest

United States Patent Office.

MARTIN LANDENBERGER, OF PHILADELPHIA, PENNSYLVANIA.

Design No. 4,234, dated July 19, 1870.

DESIGN FOR A SHAWL.

The Schedule referred to in these Letters Patent and making part of the same.

To all whom it may concern:

Be it known that I, MARTIN LANDENBERGER, of Philadelphia, in the county of Philadelphia, and in the State of Pennsylvania, have invented a certain new and useful Design for Shawls; and do hereby declare that the following is a full, clear, and exact description thereof, reference being had to the accompanying drawing and to the letters of reference marked thereon, making a part of this specification.

The design for shawl is shown in the annexed drawing.

Figure 1 is a view of the body of the shawl, and

Figure 2 is a view of the border.

A is the body of the shawl, of one color, made in such manner that the stitches will run in an oblique or diagonal manner.

The border is formed of two narrow dark stripes, C C, between which are three wider stripes, B B, of dark color, and placed at suitable intervals. The

spaces between the stripes B and C are filled up with stripes D D, of different colors and widths.

All the stripes, B, C, and D, are mottled, as shown, and run on all sides of the shawl, in the same order, from the center, and the colors follow in the same order; but on two opposite sides the colors of the stripes D D are of a darker shade than those on the other two sides.

It will be seen that at the corners of the shawl the stripes C C form a square, within which are sixteen squares, H H, of variegated colors, these squares being separated by the stripes B B.

What I claim is—

The design for shawl, as shown and described.

In testimony that I claim the foregoing, I have hereunto set my hand this 21st day of May, 1870.

Witnesses: MARTIN LANDENBERGER.

J. M. MASON,

C. L. EVERETT.
